UNITED STATES PATENT OFFICE

116,626

DESIGN FOR A BREAD WRAPPING MACHINE

Charles H. Petskeyes, Davenport, Iowa, and Israel C. Gellman, Rock Island, Ill., assignors to Gellman Manufacturing Company, Rock Island, Ill., a corporation of Illinois

Application November 2, 1938, Serial No. 80,832

Term of patent 14 years

To all whom it may concern:

Be it known that we, Charles H. Petskeyes and Israel C. Gellman, citizens of the United States, and residents of Davenport, in the county of Scott and State of Iowa, and Rock Island, in the county of Rock Island and State of Illinois, respectively, have invented a new, original, and ornamental Design for a Bread Wrapping Machine, of which the following is a specification, reference being had to the accompanying drawings, forming a part thereof, and in which:

Fig. 1 is a perspective view of a bread wrapping machine showing our new design; and

Fig. 2 is a perspective view of the side not shown in Fig. 1; and

Fig. 3 is an end elevational view of the machine, taken from the right of Fig. 1.

We claim:

The ornamental design for a bread wrapping machine, as shown.

CHARLES H. PETSKEYES.

ISRAEL C. GELLMAN.
